HAND STAMP

Max Mann, New York, N. Y.

Application September 20, 1948, Serial No. 148,659

Term of patent 14 years

(Cl. D64—10)

To all whom it may concern:

Be it known that I, Max Mann, a citizen of the United States, residing at New York, in the county of New York and State of New York, have invented a new, original, and ornamental Design for a Hand Stamp, of which the following is a specification, reference being had to the accompanying drawing, forming part thereof.

Fig. 1 is a side elevational view of a hand stamp showing my new design;

Fig. 2 is a top plan view thereof;

Fig. 3 is a front end elevational view thereof taken from the left of Fig. 2.

I claim:

The ornamental design for a hand stamp, as shown.

MAX MANN.
